UNITED STATES PATENT OFFICE.

ALBERT BOURRIEU, OF CHICAGO, ILLINOIS.

SPARK PLUG.

Application filed August 4, 1923. Serial No. 655,676.

This invention relates to improvements in ignition devices and more particularly to spark plugs for internal combustion engines.

An object of the invention is to provide a suitable spark plug for internal combustion engines which will have one of its electrodes hollowed out to receive a quantity of mercury.

Another object of the invention is to provide a spark plug which will have one of its electrodes hollowed out and adapted to receive a supply of mercury and will also be provided with spaced grooved electrodes in sparking relation with said first mentioned electrode.

A further object of the invention is to provide a suitable spark plug for internal combustion engines which will be highly efficient in use and quite inexpensive to manufacture.

A further object is to provide means to keep the center pin of the spark plug free from all carbon or rust at all times, so that the point of contact is always clear.

Other objects will appear as the description proceeds.

In the accompanying drawing which forms a part of my application,

The single figure represents a transfer sectional view through my improved spark plug.

Like characters of reference are used throughout the following specification and the accompanying drawings to designate corresponding parts.

The body or shell 1 of the spark plug is provided adjacent its upper ends with the internal screw threads 2 and at its lower end with the centrally extending inclined seat 3.

A hollow insulator 4 is provided at its lower end with the enlarged portion 5 which is adapted to seat down on the asbestos copper washer 6 on the seat 3. A second washer 7 is positioned on the upper shoulder 45 of the enlarged portion 5 and is securely clamped together with said insulator by means of the exteriorly screw threaded nut 8.

A central rod or electrode 9 is provided adjacent its lower end with the flange 10, which is adapted to seat in a correspondingly shaped socket at the lower end of the insulator and is further provided at its extreme lower end with the threaded extension 11. This rod or electrode 9 extends up through the central portion of the insulator 4 and

somewhat above the same and is screw threaded as at 12 at its upper extremity. An asbestos washer 13 is positioned about the rod or electrode 9 and a portion thereof is snugly fitted into the interior opening in the insulator 4. A brass washer 14 is positioned about said electrode 9 and on top of the asbestos washer 13 and is securely clamped down by means of the locking nut 15. A suitable binding post nut 16 is threaded on the threaded extremity 12 of the electrode 9 and serves to clamp the ignition wires in position thereon.

The electrode 9 has also connected with it a lower portion or hollow tube 17 which is interiorly threaded at its upper end and adapted to the threaded extension 11 of the said electrode. The tube 17 is adapted to hold a quantity of mercury 18 the action of which will later be explained.

A pair of positive electrodes 19 are threaded into the lower end of the shell 1 of the spark plug and are bent inwardly and then outwardly adjacent their lower extremities. The lower ends of the electrodes 19 are grooved as at 20 on the sides adjacent the hollow tube 17.

The action of the plug will be as follows:—When the high tension current passes through the mercury it will cause the same to permeate by reason of the electrons passing through the mercury and pores of the steel walls of the tube. This action keeps the outer surface of the electrode or tube always smooth, clean and shiny for an indefinite period of time. It often happens that when an internal combustion engine is running that oil will be pumped by the pistons and be thrown on the electrodes of the spark plugs. If this happens the oil will run down along the grooves in the electrodes and drop off leaving the sharp edges at the opposite sides of said grooves always clean and ready for efficient sparking between the same and the negative electrode.

There will be a vacuum inside of the porcelain insulator which will prevent the expansion and cracking of the said insulator which is often caused by the over-heating of the same. Many minor changes in detail of construction may be resorted to without departure from the spirit of the invention.

Having thus described my invention what I claim as new and desire to secure by Letters Patent of the United States is:

1. A spark plug comprising a shell, a hol-

- low insulator carried thereby, an electrode adapted to extend through said insulator, the interior portion of said insulator being exhausted of air, a mercury filled tube 5 tachably secured to the lower end of said electrode and a pair of grooved positive electrodes adjacent the lower end of said mercury filled tube.
2. In a spark plug, the combination with 10 a shell, of a hollow insulator, an electrode adapted to extend through said insulator, an asbestos washer positioned partly within the top of the insulator, of means for clamping said washer in place, the hollow insulator 15 being exhausted of air adapted to prevent the expansion and cracking of said insulator by overheating.
3. In a spark plug, the combination with a shell, of a hollow insulator, an electrode adapted to extend through said insulator, a 20 mercury filled tube detaehably secured to the lower end of said electrode, the mercury filled tube having a relatively thin wall adapted to enable mercury vapor caused by high temperature to permeate through the 25 walls of the central electrode, thereby causing accumulated carbon to dissolve.

In testimony whereof he affixes his signature.

ALBERT BOURRIEU.
